W. F. SELLERS.
AIR SEAL FOR KILNS.
APPLICATION FILED APR. 4, 1922.

Patented Nov. 7, 1922.

2 SHEETS—SHEET 2.

Inventor:
William F. Sellers
by James J. Chantler
his Attorney

UNITED STATES PATENT OFFICE.

WILLIAM F. SELLERS, OF BRANDYWINE HUNDRED, DELAWARE, ASSIGNOR TO EDGE-MOOR IRON COMPANY, OF EDGEMOOR, DELAWARE, A CORPORATION OF DELAWARE.

AIR SEAL FOR KILNS.

Application filed April 4, 1922. Serial No. 549,526.

To all whom it may concern:

Be it known that I, WILLIAM F. SELLERS, a citizen of the United States of America, and resident of Brandywine Hundred, 5 county of New Castle, State of Delaware, have invented a certain new and useful Improvement in Air Seals for Kilns, of which the following is a true and exact description, reference being had to the accompanying drawings, which form a part thereof.

My invention relates to rotary cement kilns and has for its object to provide an improved air seal between the end of the kiln 15 and the opening in the kiln housing through which the gases escape from the kiln into a flue. The object of my invention is to provide an air seal the parts of which are especially designed to permit of the convenient 20 assembly and detachment of the parts whereby replacement of one member can be conveniently and rapidly effected, the air seal being especially designed for the severe conditions of use.

25 The nature of my improvements will be best understood as described in connection with the drawings in which

Figure 1 is a sectional elevation through the end of the kiln and the portion of the 30 housing with which the kiln registers showing the air seal device in section.

Figure 2 is an enlarged sectional view of the air seal device with an indication in dotted lines at the bottom of the view showing how 35 the air seal can be conveniently applied to a kiln having a tapered end.

Figure 3 is in part a face view taken on the section line 3—3 with certain members of the air seal construction shown to very full extent.

40 Figure 4 is a sectional view on the line 4—4 of Fig. 3 shown on an enlarged scale.

Figure 5 is a face view of the flat or seal ring indicated at J in the other drawings, 45 and

Figure 6 an edge view of this ring.

A indicates the end of the kiln. B the housing and B' the opening through the housing through which the gases pass from 50 the kiln to the flue. C is a channel iron frame secured to the face of the housing around the opening B' to which is secured the cylinder indicated at D. The space between the frame C and cylinder D can be con-

veniently filled with concrete as indicated at 55 L, Fig. 3. D' is the longitudinally extending key secured to the inside of the cylinder D, preferably two such keys being supplied on opposite sides of the cylinder. E, E, are spaced flanges secured to the end of the kiln 60 and preferably made in the form of cast iron angles as indicated.

Extending inward from the edges of the flanges E are slots indicated at E', these slots being formed, as shown, in a series of sets, 65 one set for each section of the sectional ring to be attached to the flange and each slot of each set being parallel to each other and parallel to a central radial line. F, F, are sectional rings to be attached to the flanges E, 70 E, the sections being secured together by spliced plates indicated at H and bolts and nuts I, I', as clearly shown in Figs. 2 and 3. Each section of the ring F has projecting outwardly from it a bolt indicated at G, see 75 Figs. 2 and 4, the bolts being so located that one will register with each of the slots E' and the ring sections being firmly secured to the flanges E by nuts G' screwing on the bolts and against the outer sides of the 80 flanges, as shown in Fig. 4. J is a flat ring fitting in the cylinder D and extending inward at right angles to this cylinder. This ring is preferably formed with slots J' which fit over the keys D' so as to prevent 85 the rotation of the plate while permitting it to move freely longitudinally of the cylinder D. The ring J fits between rings F, F, as shown in Fig. 2 and is preferably made up, as shown, of two sets of sectional plates lap- 90 ping each other and secured together by rivets indicated at K. One set of plates is indicated at J' and the other at J'', Fig. 2.

Where the end of the kiln is tapered, as indicated in dotted lines at a', Fig. 2, a platform a' to which the flanges E, E, can be attached, can readily be provided by securing to the tapered end of the kiln a bent plate indicated in dotted lines at a''. Owing to the warping of the kiln, the end of it to which 95 the air seal is in part attached and in part connects, will generally move in an eccentric path with regard to the cylinder D and I have indicated in dotted lines at c, d, the relative positions of these stationary parts with regard to the end of the kiln which may occur in extreme cases, showing also in dotted lines at j the extreme inward position of the 100 105

ring J, corresponding with this extreme eccentricity of movement of the end of the kiln in the cylinder D.

It will be obvious that if it becomes necessary to remove for repair or replacement the ring J, this can readily be effected by removing the outer ring F and it will also be obvious that outer ring F can be removed by detaching the spliced plates H holding its sections together, loosening the nuts G and removing the sectional ring, section by section, the removal of the ring sections being made practicable and easy by the described arrangement of the slots E' in parallel sets, one set for each ring section which makes practicable an outward rotary movement of the ring section, its attached bolts G moving readily through the parallel slots.

Having now described my invention, what I claim as new and desire to secure by Letters Patent, is:

1. In combination with a rotary cement kiln and a kiln housing into which the kiln opens, means for sealing the space between the end of the kiln and the housing, consisting of a cylinder surrounding the opening into the housing and secured to the housing, in combination with a flat ring extending inward from and at right angles to said cylinder and movable longitudinally therein, spaced flanges secured to and extending outwardly from the end of the kiln and rings made up of detachable sections detachably secured on the inside of the flanges and extending outwardly therefrom over the inner edge of the inwardly extending ring aforesaid.

2. In combination with a rotary cement kiln and a kiln housing into which the kiln opens, means for sealing the space between

the end of the kiln and the housing, consisting of a cylinder surrounding the opening into the housing and secured to the housing, in combination with a flat ring extending inward from and at right angles to said cylinder and movable longitudinally therein, spaced flanges secured to and extending outwardly from the end of the kiln, said flanges having a series of sets of slots cut through their outer edges, the slots of each set being parallel to each other and to a radial line passing through the center of the set and rings made up of detachable sections equal in number to the sets of slots cut in the flanges, detachably secured on the inside of the flanges by bolts secured to the sections of the rings and passing through the slots in the flanges, said sectional rings extending outwardly from the flanges over the inner edge of the inwardly extending ring aforesaid.

3. In combination with a rotary cement kiln and a kiln housing into which the kiln opens, means for sealing the space between the end of the kiln and the housing, consisting of a cylinder surrounding the opening into the housing and secured to the housing, in combination with a flat ring extending inward from and at right angles to said cylinder and movable longitudinally therein, said ring being formed of lapping sectional plates secured together, spaced flanges secured to and extending outwardly from the end of the kiln and rings made up of detachable sections detachably secured on the inside of the flanges and extending outwardly therefrom over the inner edge of the inwardly extending ring aforesaid.

WM. F. SELLERS.
